UNITED STATES PATENT OFFICE.

MARCEL ROCHAS, OF PARIS, FRANCE, ASSIGNOR TO DAVID CRYSTAL, INC., OF NEW YORK, N. Y., A CORPORATION OF NEW YORK.

DESIGN FOR A DRESS.

Application filed April 1, 1927. Serial No. 21,433. Term of patent 3½ years.

To all whom it may concern:

Be it known that I, MARCEL ROCHAS, a citizen of France, and a resident of Paris, France, 100 Fg. St. Honore, have invented a new, original, and ornamental Design for Dress, of which the following is a specification, reference being had to the accompanying drawing, forming part thereof.

Figure 1 is a front view of a dress, showing my new design, the same being shown on a figure.

I claim:

The ornamental design for a dress, substantially as shown.

M. ROCHAS.
